UNITED STATES PATENT OFFICE.

ADAM L. CRANE, OF FORT MILL, SOUTH CAROLINA.

CEMENT TIE AND RAIL FASTENER.

1,423,600.

Specification of Letters Patent. Patented July 25, 1922.

Application filed February 18, 1922. Serial No. 537,551.

To all whom it may concern:

Be it known that I, ADAM L. CRANE, a citizen of the United States, residing at Fort Mill, in the county of York and State of South Carolina, have invented certain new and useful Improvements in Cement Ties and Rail Fasteners, of which the following is a specification, reference being had to the accompanying drawings.

10 It is the purpose of the present invention to provide a tie and rail fastener of the present character, similar to but different from the construction of tie and rail fastener set forth, claimed and illustrated in the patent

15 to Adam L. Crane, No. 1,373,601.

In this patent cushioning members are used, but which are dovetailed in the tie. In the present invention it is the aim to eliminate the dovetail construction, and in 20 lieu thereof, simply insert the cushioning members in recesses of the tie.

Furthermore in said patent the cushioning members are supported upon a plate embedded in the tie, but in the present construction it is the aim to eliminate this plate, and in lieu thereof utilize reinforcing rods, arranged adjacent the upper surface of the tie and adjacent the lower surface of the tie. In arranging these reinforcing members or rods, it is the aim to upturn the ends 25 of the lower reinforcing rods so as to extend beyond the upper reinforcing rods, thereby giving greater strength to the cement structure of tie.

30 In the aforesaid mentioned patent there is no means for pulling the tie in place. In other words should it be necessary to repair the road, by extracting a worn tie, and in its stead to insert a new tie, there is no means

35 by which the tie can be pulled into place under the rails. Hence, in the present invention, it is the aim to extend the upper central reinforcing rod beyond the upper ends of the tie to form hooks which have 40 rings by which the tie can be pulled into place under the rails. The ends of the tie are formed with cavities adjacent the hooks, in order to permit the rings to be connected 45 to the hooks.

50 Still another purpose is the provision of upper and lower transversely disposed reinforcing plates disposed at points centrally between the ends of the tie, above and below the upper and lower reinforcing rods, in combination with perpendicular rods connecting the transverse plates, to insure ri-

gidity for the reinforcing means, yet permit of a reasonable amount of elasticity of the tie, while in place.

It has been found that ties which are flat upon their under surfaces, cause what has been termed as a center-bind. In other words the ballast of the road adjacent the sides thereof becomes depressed, causing a crowding of the ballast near the center of the bed, hence causing the ties to rock.

It is, therefore, the purpose of the present invention to obviate this difficulty by constructing a tie, which is thicker in the center than at the ends, the under surface of the tie tapering from the thicker portion to the ends of the tie. From practical experience it has been found that this construction of tie will obviate the so called center-bind of the tie, in other words will obviate the crowding or collecting of the ballast near the center of the road bed, and thereby will permit the ties to lie or assume their proper positions, and to such an extent as to permit the rolling stock to travel without undue 80 rocking movement.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

90 The invention comprises further features and combination of parts, as will be herein-after set forth, shown in the drawings and claimed.

In the drawings:-

95 Figure 1 is a view in perspective of the improved cement tie and rail fastener constructed in accordance with the invention;

Figure 2 is an enlarged detail perspective view of the reinforcing means for the concrete or cement filler of the tie;

Figure 3 is a longitudinal sectional view on line 3-3 of Figure 1;

Figure 4 is a bottom plan view of the tie;

Figure 5 is a plan view of the tie;

Figure 6 is a cross sectional view on line 6-6 of Figure 1, showing the arrangement of the reinforcing tie rods;

Figure 7 is an enlarged detail sectional view of one-half of the tie, more clearly showing another form of upper reinforcing or tie rod; and

Figure 8 is a detail transverse sectional view of the tie showing a modified construction of a recess 14.

Referring to the drawings, 1 designates the body of the tie, which may be constructed of any suitable plastic material, such as cement, concrete or the like. The upper surface of the tie adjacent both ends is provided with recesses 2, for the reception of cushioning members or blocks 3. These cushioning members may be constructed of any suitable wood, rubber, or fibre of any kind, such as will permit of a cushioning effect for the rails. Suitable plates 4 engage upon the cushioning members or blocks 3, and are provided with V-shaped projections 5, to pierce or extend into the cushioning members, to prevent movement of the plates. These plates support the rails 6. The recesses 2 may be dovetailed, as shown in the aforesaid patent, or otherwise constructed, so long as the cushioning members or blocks are held in position and under the rails.

Engaged upon the upper surfaces of the plates 4 and overlying the base of the rails are clamping plates 7, which are held against rocking movements by means of the lugs 8 which rise from the plates 4. Suitable bolts 9 pass upwardly through the tie, through the cushioning members or blocks 3, through the plates 4, and the clamps 7, and are provided with nuts 10 on their upper ends, to not only hold the bolts in place, but also secure the clamps in position. Additional bolts 11 pass upwardly through the tie, through the cushioning members or blocks 3, and also through the plates 4. In order to apply the bolts 11, they are inserted downwardly through the plates 4 and through the cushioning members and through the tie. These bolts 11 on their upper ends are provided with heads 12, laterally extended, to overlie the bases of the rails, in order to cooperate with the clamping plates 7 for the purpose of holding the rails in position. In order to hold the bolts 9 and 11 in position, plates 13 are positioned adjacent the under surface of the tie. In fact these plates 13 are countersunk in diagonally disposed recesses 14 of the under surface of the tie. These recesses 14 are open at their ends, and as shown in Figure 8 the central portions of these recesses 14 may or may not be closed, in other words filled up. If these central portions 14 are closed, the plates 13 may be inserted from either side of the tie, or preferably molded in the tie, when the tie is constructed. The bolts 9 and 11 pass upwardly through the tie, and through the plates 13, thereby insuring a secure anchorage for the bolts, sufficiently to not only retain the clamps 7, but also the rails 6 in place. The bolts 9 have nuts upon their

ends, in order to permit them to be easily adjusted. The heads 12 are on the upper ends of the bolts 11, hence the nuts 15 are on their lower ends, thereby necessitating a wrench being inserted in the recess 14, to turn the nuts 15 on or off. It is obvious that the plates 13 may be easily renewed, if necessary, by simply detaching the nuts 10 and 15, and extracting the bolts, which may permit the plates to be moved transversely of the tie.

Arranged longitudinally of the tie and embedded in the cement or concrete thereof adjacent the upper surface of the tie are reinforcing rods 16, which at points adjacent the cushioning members or blocks 3 are made to conform to the contour of the blocks. Any number of these rods 16 may be used. However it has been found convenient and practical to use only three. It is obvious that the reinforcing rods 16 may or may not be straight for their full lengths as shown in Figures 3 and 7 clearly. In other words Figure 3 illustrates the rods 16 as conforming to the contour of the cushioning members or blocks 3, whereas Figure 7 discloses these reinforcing rods 16 as being straight. In other words in Figure 7 there are no offset parts, such as shown at 17 in Figure 3.

Arranged and embedded in the tie, adjacent the under surface thereof and conforming thereto are lower longitudinally disposed reinforcing rods 18, the ends of which are upturned as indicated at 19.

The ends of the tie have suitable cavities 20, which permit rings 21 to be connected to the hooks 22, which are formed upon the ends of the reinforcing rods 16. It will be noted that the hooks 22 are countersunk due to the provision of the recesses 20, and it will be noted that by means of the rings 21 an operator's hand may engage therewith, whereby the tie may be pulled into place under the rails, especially when repairing the road. In other words should it be desired to repair the road by removing an old tie and replacing it with a new one, of the construction herein illustrated, the workman may simply grasp the ring 21, so as to pull the tie transversely of the road bed and under the rails. In fact the rings 21 may be used for pulling the tie into place, even though constructing a new road.

Arranged transversely of the tie and embedded therein at points adjacent the upper and lower surfaces thereof and substantially between the ends of the tie are upper and lower metallic bars 23 and 24. The upper bar 23 extends across the upper tie or reinforcing rods, while the lower bar 24 extends transversely below the lower rods 18. By means of the metallic bars 23 and 24, the tie is reinforced transversely, and it is also reinforced longitudinally, due to the fact that

the rods 16 and 18 extend longitudinally of the tie.

As shown the central portion of the tie is thicker than the ends thereof, and this 5 construction has been found practical and essential, due to the fact that it eliminates what is called the center-bind, which is due to the removal of the ballast from under the ends of the tie.

10 In order to insert the bolt upwardly through the tie body, the ballast as well as the earth thereunder may be excavated to make room for the bolt. However, the bolts 9 and 11 may be inserted downwardly 15 through the tie body, so that the nuts may be applied from their lower ends. In this latter case it would be unnecessary to excavate the ballast or the ground thereunder.

The invention having been set forth, what 20 is claimed is:—

1. In a tie, a plastic tie body, wherein its central portion is relatively thick and has its under surface tapered or inclined upwardly from said relatively thick portion to the 25 ends of the tie, upper and lower reinforcing tie rods embedded in the tie body, the lower reinforcing tie rods conforming to the contour of the bottom of the tie, upper and lower transverse reinforcing plates or bars, 30 the upper bar overlying the longitudinal reinforcing rods, the lower bar underlying the lower longitudinal reinforcing rods, vertical rods connecting the transverse bars, rails to rest upon the tie, which is provided 35 with cushioning supports for the rails, and means for fastening the rails in position.

2. In a tie, a plastic tie body, wherein its central portion is relatively thick and has its under surface tapered or inclined upwardly 40 from said relatively thick portion to the

ends of the tie, upper and lower reinforcing tie rods embedded in the tie body, the lower reinforcing tie rods conforming to the contour of the bottom of the tie, upper and lower transverse reinforcing plates or bars, 45 the upper bar overlying the longitudinal reinforcing rods, the lower bar underlying the lower longitudinal reinforcing rods, vertical rods connecting the transverse bars, rails to rest upon the tie, which is provided with 50 cushioning supports for the rails, and means for fastening the rails in position, one end of one of the upper longitudinally extending reinforcing rods terminating in a hook countersunk in the end of the tie, and means adapted to engage said hook, whereby the tie may be pulled in place upon the road bed. 55

3. In a tie, a plastic tie body, cushioning members countersunk in the upper surface of said body adjacent its opposite end, rails 60 engaging said cushioning members, means overlying the base of the rails and passing through the cushioning members and provided with anchoring devices embedded in the under surface of the tie for holding the 65 rails in place, upper reinforcing rods embedded in the tie and having their end parts shaped to conform to the cushioning members, lower longitudinally extending reinforcing rods embedded in the tie body, upper 70 and lower transverse reinforcing bars, the upper bar overlying the upper longitudinal reinforcing rods while the under bar underlies the lower longitudinal reinforcing rods, and means connecting the upper and lower 75 reinforcing bars.

In testimony whereof I hereunto affix my signature.

ADAM L. CRANE.
